UNITED STATES PATENT OFFICE.

GIUSEPPE BELLUZZO, OF MILAN, ITALY.

STEAM-TURBINE.

No. 903,046.

Specification of Letters Patent.

Patented Nov. 3, 1908.

Application filed June 4, 1907. Serial No. 377,235.

To all whom it may concern:

Be it known that I, GIUSEPPE BELLUZZO, mechanical engineer, subject of the King of Italy, residing at Milan, Italy, No. 1 Via 5 Paolo Frisi, have invented new and useful Improvements in Heat Prime Movers with Multiple Expansion, Especially in Steam-Turbines, of which the following is a specification.

10 It is well known that the common cycle followed by the motive fluid in a steam plant (reciprocating engine or turbine) has a very low caloric efficiency, for on one side it does not correspond to the conditions of the cycle 15 of Carnot and on the other side nearly the whole of the heat transmitted to the motive fluid in the boiler passes over into the condenser.

20 The purpose of the present invention is that of increasing the said efficiency, to which effect the following means have been resorted to, namely:

25 1. To heat within the turbine a weight of water equal to that one of the steam consumed and cause the same to move in an opposite direction to the steam. This water is then led into the boiler.

30 2. To cause another liquid substance, the upper limit curve of which has its points situated underneath the upper limit curve of steam, to evaporate and act upon the same turbine. Such a substance could be for instance sulfur dioxid, alcohol, CCl_4 &c. &c.

35 In both cases the steam is caused to expand polytropically (beginning from the initial temperature and pressure depending upon those of the boiler and the opening of the admission valve controlled by the governor) into a first set of guide vanes or distributor (impulse turbine, or turbine with multiple wheels) or in a series, of distributors and of successive wheels (reaction turbines) until it reaches a certain pressure (which in the case of overheated steam can be such 40 that the final temperature of the expansion is still higher than that one corresponding to the saturated steam at the admission pressure.) Thence the steam is caused to undergo a transformation at constant pressure, 45 causing it to give up heat either to the water or to some other fluid, which is moving in the turbine in opposite direction and has already been heated by successive transformations of the steam. Afterwards the steam is still 50 caused to expand either in a successive distributor or in another set of distributors and

wheels, in order to cause it to undergo a new transformation at constant pressure, when it gives up heat to the same fluid and so forth, until with successive expansions and losses of 50 heat the steam has gradually reduced its pressure, its temperature and its specific volume so that at the discharge before the condenser there will be either water, when the second one of the solutions indicated is 55 adopted, or very wet steam, when the first one is adopted, at the temperature of the condenser which, on account of the small amount of heat to be taken off, preferably is 60 a jet condenser.

65 70 The accompanying drawings show by way of example only how the present invention may be carried out.

75 Figure 1 is a diagrammatic view of a reaction turbine of the Parsons type, the same being modified so as to embody my present invention; Fig. 2 is a detail sectional view of a portion of a turbine having fluid-compressing fans embodied therewith; and Fig. 3 is a detail sectional view of a portion of a turbine 80 having a vertical axis and showing a modified arrangement for the circulation of the secondary or auxiliary fluid.

85 Fig. 1 diagrammatically shows a longitudinal section of a reaction turbine of Parsons type modified in such a way as to utilize a great deal of the heat of evaporation, when it is the case of steam, giving up the same, as already told, either to the water to be heated within the boiler or to the other fluid.

90 95 What will be hereinafter set forth can also be applied to a turbine with multiple wheels of the impulse instead of the reaction type.

According to Fig. 1 the turbine (Fig. 1) has been divided into five sets or groups of wheels g_1, g_2, g_3, g_4, g_5 . At the end of each set there is a heating vessel A_1, A_2, A_3 , into which discharges the exhaust steam of the previous set; the heating vessels A_1, A_2 are connected in series.

100 105 110 In Fig. 1 the arrows 1 to 8 respectively show: 1 the delivery pipe of the first wheel of a centrifugal pump as shown in the drawing; 2 the suction pipe of the second wheel of said centrifugal pump; 3 the delivery pipe of the second wheel of the aforesaid pump; 4 the suction pipe of the third wheel of said pump; 5 the delivery pipe of the third wheel thereof; 6 the suction pipe of the fourth wheel thereof; 7 the delivery pipe of the fourth wheel thereof; 8 the suction pipe of the fifth wheel of the same centrifugal pump.

The second fluid entering at 1 from the last heater A_5 passes to A_4 , from this one to A_3 , where the steam produced by means of the tube b acts upon the last group of wheels. 5 On the bottom of A_3 the heated, but not evaporated liquid passes to the suction pipe 2 of the second wheel of the centrifugal pump (the first wheel of which forces the liquid into pipe 1). Said centrifugal pump forces 10 the liquid into heater A_2 , where it is evaporated; the produced steam is led to act upon the set of wheels g_4 by means of pipe c and so forth.

The heaters for the secondary or auxiliary 15 fluid may be of any appropriate construction that will permit the flow of the steam or primary fluid and the secondary fluid therethrough, the heaters shown in the present instance being of the cellular or tubular type, 20 such as employed in the water cooling systems of automobiles, the secondary or auxiliary fluid flowing through a cell or tank, and the steam or primary fluid flowing through the tubes which extend through such tanks 25 as shown conventionally upon the drawing.

From the bottom of A_1 starts the tube which leads to the suction pipe 6 of the fourth wheel of the centrifugal pump, which through 7 forces the warm liquid into the 30 heater A_0 through which goes the steam escaping along the first balance piston S_1 .

The heater A_3 connected with A_4 by means 35 of the tube b_1 utilizes the heat of the steam, which escapes along the second piston S_2 , and the produced steam joins to that one given by the heater A_3 . The discharge of S_2 , through a tube not shown in the drawing crosses A_5 . Between S_1 and S_2 , between S_2 and S_3 for the same aim injections of water 40 can be made.

Fig. 2 diagrammatically shows a partial section either of an impulse, or a reaction turbine with multiple wheels; same is the section of the first set of wheels, as for the successive ones the same disposition is repeated. Namely, always for the same aim, it is supposed that at the exhaust of the last set a pump of any type (in the drawing a set of centrifugal fans connected in series) sucks up 50 the small quantity of vapor of the second fluid, which is formed there, compresses and forces the same through a heater applied at the exhaust of the penultimate set, when it is again compressed and so forth. At the same time the liquid fluid gathered at the exhaust is injected into the last heater, taken up from the latter, injected into the penultimate one and so forth. If the water is to be heated, the hot water is caused to circulate by a centrifugal pump with multiple wheels connected 55 in series either separated from the turbine, or in some way embodied in the same.

Fig. 2 shows a part of the second set of wheels g_2 , the fans v_1 connected in series, 60 which from t_2 receive the vapor of the second

fluid which comes from a successive heater after having flown through the heater A_1 . The steam which leaves the set g_1 flows through the heater A_1 and passes to the set 70 g_2 . Through the tube a the hot fluid not evaporated by the heaters A_2 , A_3 enters A_1 ; the fluid not evaporated in A_1 escapes from t and can pass into a heater surrounded by the combustion gases of the boilers. The vapor 75 of the second fluid compressed by the fans v_1 flows through the tube t_1 and is subjected to a further compression in v ; thence it escapes as shown by the arrow g , when it is either admitted to the second set of wheels g_2 , or over-heated and mixed with the steam arriving 80 from B. The fans v also act as dummy pistons balancing the axial thrust of the turbine.

Lastly Fig. 3, where the arrow 10 indicates the entering of the steam and the arrow 11 indicates the passage to the centrifugal pump 85 with multiple wheels, not shown in the drawings, relates to the application of the same principle and the same elements to an impulse turbine with vertical axis and multiple stages connected in series. (The disposition substantially remains the same even when it is 90 the case of impulse turbines with horizontal axis).

$r_1 r_2 r_3 r_4$ are the running wheels of the turbine proper $v_1 v_2 v_3 v_4$, the sets of fans or rotary compressing pumps, $c_1 c_2 c_3 c_4$ are collecting chambers at the ends thereof; $p_1 p_2 p_3$ are pipes crossing the turbine casing and communicating with the centrifugal pump; 1, 2, 3 are spaces connecting the fans $v_1 v_2 v_3$ 100 with the heaters $A_1 A_2 A_3$. The vapor of the second fluid at the exhaust 4 of the wheel r_4 is compressed by the fan v_4 and through the tube t_4 sent into the heater A_3 together with the condensed water collecting within the 105 tube b . The generated vapor is compressed within the pump or fan v_3 and passes from c_3 into A_2 through the tube t_3 ; the hot water through the tube p_3 is also conveyed into A_2 by means of the centrifugal pump and the 110 process goes on in the prescribed manner until after the first heater A_1 the vapor along 1 passes to the pump v_1 and from c_1 it goes on through the tube t_1 , in order to get dried and over-heated when it joins the steam, which is 115 coming from the boiler. Therewith the advantage of controlling the motive power with the systems commonly in use is obtained.

Any suitable liquid or fluid may be employed as a secondary or auxiliary fluid, the 120 desideratum being to employ a secondary or auxiliary liquid of such a character as will readily absorb an appropriate proportion of the heat which is given up by the steam or other primary fluid. Gaseous sulfur dioxide (SO₂) is extremely soluble in water, water being capable of absorbing about forty volumes of this gas at a temperature of 20°C. although liquid sulfur dioxide is almost insoluble. The separation of the water from the 125 130

SO₂ could therefore be obtained by compressing the mixture, liquefying SO₂ when it will separate from the water by reason of the difference of specific weight, the density of liquid SO₂ being about 1.04 times the density of water. If so desired, however, water alone may be employed as the secondary or auxiliary fluid, and practical tests have demonstrated that water alone may be so used.

Having now fully described the present invention and how the same is to be carried out, what I claim is:

1. An elastic fluid prime mover having fluid driven elements for expansively utilizing a primary driving fluid, means for conducting said primary driving fluid from one element to the other, and means for conducting a second fluid through the prime mover under the influence of the heat of the primary fluid whereby an increase in the temperature of the secondary fluid is caused during a corresponding decrease in the temperature of the primary fluid.
2. An elastic fluid prime mover having fluid driven elements for expansively utilizing a primary driving fluid, means for conducting said primary driving fluid from one element to the other, means for conducting a second fluid through the prime mover under the influence of the heat of the primary fluid whereby a rise in temperature of the secondary fluid is caused during the decrease in temperature of the primary fluid, and means for conducting the secondary fluid to the fluid driven elements of the prime mover whereby the energy thereof may be utilized.
3. An elastic fluid prime mover having fluid driven elements, means for conducting a primary driving fluid in a given direction successively from one element to the other, and means for conducting a secondary fluid through the prime mover in an opposite direction to the direction of flow of the primary fluid, the secondary fluid being subject to the heat of the primary fluid.
4. A multiple expansion turbine having a plurality of fluid driven elements, means for conducting a primary driving fluid through said turbine and successively from one element thereof to the other, and means for conducting a secondary fluid through said turbine in a direction reverse to the direction of flow of the primary driving fluid, the secondary fluid being subject to the temperature influences of the primary fluid.
5. A multiple expansion turbine having a plurality of fluid driven elements, means for

conducting a primary fluid successively from one element to another, heaters arranged between the respective fluid driven elements and subject to the heat of the primary driving fluid, and means for conducting a secondary motive fluid successively through the said heaters.

6. A multiple expansion turbine having a plurality of fluid driven elements, means for conducting a primary driving fluid successively from one of said elements to another, a set of heaters arranged between the respective fluid driven elements and subject to the temperature conditions of the primary driving fluid, means for conducting a secondary driving fluid successively through said heaters in a direction reverse to the direction of flow of the primary driving fluid, and means for conducting the secondary driving fluid, the temperature of which has been increased in passing through said heaters to the fluid inlet of the turbine.

7. A multiple expansion turbine provided with a plurality of fluid driven elements, means for conducting a primary driving fluid successively from one of said elements to another, means for conducting a secondary fluid through said turbine under the influence of the heat of the primary fluid, and compressing devices for causing a circulation of said secondary fluid during the operation of the turbine.

8. A multiple expansion turbine provided with a set of fluid driven elements adapted to receive a primary driving fluid, means for conducting a secondary driving fluid successively from one of said elements to another under the influence of the heat of the primary fluid, and a centrifugal pump combined with the fluid driven elements of the turbine for producing a circulation of the secondary fluid under pressure.

9. An elastic fluid prime mover having fluid driven elements, means for conducting a primary driving fluid successively from one of said elements to another, and means for conducting a secondary or auxiliary fluid through the prime mover under the influence of the heat of the primary driving fluid, said fluid being vaporizable at a temperature lower than that of the primary driving fluid.

In testimony whereof I have signed my name to this specification in the presence of two subscribing witnesses.
